ICE REMOVING APPARATUS FOR AIRFOILS

John O. Antonson, Akron, Ohio, assignor to The
B. F. Goodrich Company, New York, N. Y., a
corporation of New York

Application March 21, 1944, Serial No. 527,388

5 Claims. (Cl. 244—134)

1

This invention relates to protective apparatus for airfoils and especially to inflatable apparatus for preventing the accumulation of ice thereon.

While prior constructions of inflatable apparatus mounted at the leading edges of wings and other airfoils have been utilized advantageously in ice prevention under most conditions, the action of such apparatus under some icing conditions of particular severity has not been effective to obtain the desired full cleanliness of ice removal and ice caps have at times not been broken and removed with the full promptness and thoroughness desired.

Objects of this invention are to provide improved apparatus for preventing with increased effectiveness the accumulation of ice on the leading edge of an airfoil; to provide for promptly breaking and loosening ice caps on the leading edge for their removal by the ambient airstream; to provide for imparting substantial stretching force to a stretchable portion rearward of an expandable zone during a phase of the expansion of such zone and for exerting little or no stretching force on the stretchable portion during a subsequent phase of such expansion; to provide for expanding locally a portion of the expandable zone to a relatively high degree of curvature as compared to the curvature of adjacent expandable portions upon expansion of the latter; to provide for maintaining the desired aerodynamic characteristics of the airfoil; and to provide thinness and simplicity of construction, convenience of manufacture and effectiveness of operation.

These and other objects and advantages of the invention will be apparent from the following description.

In the accompanying drawings which form a part of this specification and in which like numerals are employed to designate like parts throughout the same,

Fig. 1 is a perspective view of protective apparatus mounted on the leading edge of an airplane wing, and constructed in accordance with and embodying the invention, parts being broken away and in section.

Fig. 2 is a plan view from above of the apparatus or covering before being installed on the wing, parts being broken away.

Fig. 3 is a cross-sectional view of the covering installed on the wing showing a cap-breaking tube in the inflated condition with little or no stretching of the stretchable portions rearwardly of such tube, and

Fig. 4 is a view like Fig. 3 but showing a pair of associated stretching tubes in the inflated condition stretching the rearward stretchable portions in the chordwise direction.

In the embodiment of the invention illustrated in the drawings, a covering 10 comprising a body of elastic construction including resilient rubber

2

or other rubber-like material is mounted on the leading edge of a wing 11 of an airplane, for example, the wing having a nacelle 12 housing a motor for driving a propeller 13.

5 The covering 10 is mounted in a stretched condition in the chordwise direction of the wing 11 and secured to the wing skin along upper and lower attaching margins 14 and 15 of the covering extending spanwise of the wing as by attaching screws 16 extending through upper and lower marginal fairing strips 17, 18 and through the covering 10 and into the wing skin. The attaching margins 14, 15 may have reinforcing strips or bead elements 19, 20 of stiff material such, for example, as flat metal wire included therein.

10 The covering which has a relatively smooth exterior surface for promoting smooth flow of the ambient air, includes an expandable or central tube zone 19 intermediate the attaching margins 20 and stretchable portions 20, 21 extending rearwardly from such zone. The covering also includes a plurality of inflatable tubes 22, 23, 24 disposed in the tube zone 19 in series in the chordwise direction for local expanding of the zone 19 and for stretching the stretchable portions 20, 21 upon inflation of the respective tubes in a cyclic manner described hereinafter. For inflating the tubes, connector means 25 in communication with such tubes at one end of the latter may be provided. Fluid conduits 26 and 27 are connected to the connector means 25 and to suitable control equipment (not shown) and to a source of air under pressure, which equipment and source of air may be disposed, for example, within the 15 fuselage of the airplane.

15 The inner surface of the body of the covering 10 may be provided with venting channels 28 extending in the spanwise direction and spaced-apart venting grooves 29 extending in the chordwise direction, venting apertures 30 being in communication with the outer air at spaced-apart positions chordwise along such venting grooves. This subject matter of the channels and the grooves for venting action is set forth more 20 fully in the copending application of Willson H. Hunter and William C. Green, Serial No. 482,536, filed April 10, 1943, now matured into Patent No. 2,421,621, issued June 3, 1947.

25 The cap-breaking tube 23 may be relatively small in cross-section as compared to the spaced-apart stretching tubes 22, 24 which may be larger in cross-section. The cap-breaking tube 23 is positioned between the stretching tubes 22, 24 in series chordwise therewith for local stretching of the covering at the tube zone with little or no stretching of the stretchable portions 20, 21. These tubes 22, 23, 24 may be tapered spanwise in conformance with the tapered arrangement of the covering 10 as shown especially in Fig. 2. 30 The cap-breaking tube 23 is disposed preferably

immediately at the leading edge and has a wall of relatively great stretchability as compared to the associated stretching tubes 22, 24. Such wall includes in the rubber thereof reinforcing material such as stockinette or other knitted or otherwise stretchable fabric, preferably of nylon or rayon, although cotton or other suitable material may be used. The stockinette fabric is stretchable both circumferentially and longitudinally of the tube, which permits extensive stretching of the tube wall for expanding the covering locally at the tube zone to break and loosen the ice cap thereon.

For facilitating such local expanding action, it is desirable that the cap-breaking tube 23 be disposed within the covering immediately beneath the outer surface of the latter in the tube zone whereby a relatively thick body of rubber material is under such tube 23 as compared to the adjacent tubes 22, 24; whereas the latter tubes 22, 24 are disposed desirably immediately adjacent the inner surface of the covering whereby a relatively thick body of rubber material is over these tubes, 22, 24 as compared to the tube 23.

This construction is advantageous in that the tube 23 upon inflation first in the cycle tends to expand and stretch outwardly and to assume the relatively high degree of curvature afforded by a semi-circular shape in section as shown in Fig. 3, by virtue of the uniform and high stretchability of the wall thereof and also by virtue of the little or no restraint against local stretching offered by the thin resilient rubber of the covering over such tube 23. A further advantage of the construction described hereinabove is that the inner part of the covering at the tube zone 19 and the stretchable portions 20, 21 remain against the wing with negligible lifting therefrom during the inflation of the cap-breaking tube 23 thereby avoiding objectionable entrapment of air, especially at the tube zone, and subsequent objectionable "ballooning" of the covering. Also the stretching of the tube 23 is effective at the immediate leading edge region in cracking and loosening the ice cap even though the ice cap be heavy, but in this first part of the cycle need have little or no effect on rearward ice formations on the stretchable portions 20, 21.

The spaced-apart stretching tubes 22, 24 adjacent the opposite margins of the tube 23 have rubber walls including stretch-resisting textile fabric material, preferably square-woven fabric, straight-laid, for limiting the expansion of the tubes 22, 24, such fabric being relatively inextensible as compared to the fabric included in the tube 23. Such expansion-limiting or stretch-resisting fabric reinforcement resists effectively the local stretching of the rubber walls, and the tubes 22, 24 upon inflation assume an outwardly curved shape of lesser sharpness of curvature than that of the tube 23 as shown in Fig. 4, and move laterally relative to the leading edge by virtue of their spaced-apart positioning at such leading edge. This action further assists removal of any remaining broken pieces of the ice cap by moving such pieces laterally into the airstream; and this action also effectively imparts a relatively great stretching force to and uniformly throughout the extent of the stretchable portions 20, 21 and moves the latter portions outwardly from the wing 11 whereby the sheet-like ice formations on the stretchable portions are broken and loosened for prompt and thorough removal by the ambient airflow.

The stretchable portions 20, 21 comprising 75

suitable rubber-like material extend rearwardly from the tube zone 19 to the attaching margins 14, 15 and include desirably spaced-apart tear-resisting strips 31, 31 of chordwise stretchable fabric material such, for example, as Trico fabric embedded therein. The strips 31 may be located at the venting grooves 29 and extend chordwise between the margins of the stretching tubes 22, 24 and bead holding elements 32, 32 of chordwise stretchable fabric material at the attaching margins 14, 15. The stretchable fabric of the bead holding elements 32, 32 is folded around the wires 18, 18 and permits stretching of the stretchable portions 20, 21 directly to and along the bead wires 18, 18 for promoting uniformity of stretch of such portions and for uniformly stressing such wires. An offset in the covering may be provided for a flush mounting of the fairing strips 17, 17.

The fabric and rubber parts of the covering are united by vulcanization and heat under pressure.

In the operation of the apparatus 10, it is desirable that the cap-breaking tube 23 be inflated first in the cycle by admitting air under pressure through the conduit 27 and connector means 25. The tube 23 then distends outwardly to a substantially semi-circular shape in cross-section in the manner shown in Fig. 3, the wall of the tube stretching locally to a relatively great extent within itself by virtue of the stretchable action of the nylon fabric. Such distending and stretching action of the tube 23 exerts little or no stretching force upon the stretchable portions 20, 21 but cracks and loosens effectively the ice cap although the inflation of the tube 23 need have little or no effect on rearward ice formations on such portions 20, 21.

After deflation of the tube 23, the next phase in the operation of the apparatus is the inflation of the stretching tubes 22, 24, preferably simultaneously, by the air under pressure flowing through the conduit 26 and the connectors 25. These stretching tubes 22, 24 distend outwardly and move laterally relative to the leading edge because of their spaced-apart positioning thereon, and assume an expanded condition substantially as shown in Fig. 4, since the walls of the tubes include expansion-limiting fabric reinforcement which is relatively inextensible. Such action facilitates removal of any remaining broken pieces of the ice cap by moving such pieces laterally into the airstream and imparts relatively great stretching force to the stretchable portions 20, 21 while moving such portions outwardly relative to the wing, whereby the stretchable portions are stretched effectively throughout their extent thus breaking and loosening the ice formations thereon into pieces for removal by the ambient airflow over these portions of the covering. The construction and arrangement of the apparatus hereinabove described prevents effectively the accumulation of ice on the leading edge of the wing 11 while maintaining the desired aerodynamic characteristics of such wing.

Variations may be made without departing from the scope of the invention as it is defined in the following claims:

I claim:

1. Apparatus for preventing the accumulation of ice on the leading edge of an airfoil, said apparatus comprising a covering of resilient rubber-like material for said leading edge having an expansible zone and a stretchable portion between said zone and a margin of the covering,

and means for attaching said covering at said margin, the covering in said expansible zone including a plurality of adjacent inflatable portions extending spanwise in side-by-side relation along the covering and serially arranged in the chordwise direction, at least one of said inflatable portions including stretch-resisting material and being constructed and arranged for imparting upon inflation a stretching force to said stretchable portion, and another of said inflatable portions to one side of the first inflatable portion having a margin thereof extending along in close proximity to an adjacent margin of the first said inflatable portion and including material of relatively high stretchability as compared to said stretch-resisting material of the first said inflatable portion and being constructed and arranged for local inflation by virtue of its high stretchability without exerting substantial stretching force on said stretchable portion.

2. Apparatus for preventing the accumulation of ice on the leading edge of an airfoil, said apparatus comprising a covering of resilient rubber-like material for said leading edge having a spanwise-extending tube zone and a spanwise-extending stretchable portion between said zone and a spanwise-extending margin of the covering, means for attaching said covering at said margin, a pair of inflatable tubes spaced-apart chordwise and extending spanwise along the covering in said zone, said tubes comprising stretch-resisting fabric material and being constructed and arranged for imparting upon inflation a stretching force to said stretchable portion, and an inflatable tube extending spanwise along the covering in the space between and in side-by-side relation with the pair of inflatable tubes in said zone and comprising fabric material of relatively high stretchability as compared to that of said stretch-resisting fabric material of the pair of inflatable tubes and being constructed and arranged for local inflation by virtue of its high stretchability without exerting substantial stretching force on said stretchable portion.

3. Apparatus for preventing the accumulation of ice on the leading edge of an airfoil, said apparatus comprising a covering of resilient rubber-like material for said leading edge, said covering comprising a tube zone intermediate the margins of the covering and stretchable portions extending rearwardly from said zone toward said margins at opposite sides of said tube zone, means for attaching said covering at said margins, a pair of spaced-apart inflatable tubes extending along the covering in said zone, the pair of inflatable tubes including stretch-resisting fabric material in the walls thereof and being constructed and arranged for imparting upon inflation a stretching force to said stretchable portions, and an inflatable tube extending along the covering in the space between said pair of inflatable tubes in side-by-side relation therewith in said zone and including fabric material in the wall thereof of relatively high stretchability as compared to that of said stretch-resisting fabric material of the pair of inflatable tubes and being constructed and arranged for local inflation by virtue of its high stretchability without exerting substantial stretching force on said stretchable portions.

4. Apparatus for preventing the accumulation

of ice on the leading edge of an airfoil, said apparatus comprising an elastic covering including resilient rubber-like material for said leading edge having an expansible zone extending along the covering and a stretchable portion between said zone and a margin of the covering, and means for attaching said covering at said margin, the covering in said expansible zone comprising a pair of spaced-apart inflatable portions extending along the covering in said zone each including a stretch-resisting material therein and being constructed and arranged for imparting upon inflation a stretching force to said stretchable portion, and the covering in said zone comprising an inflatable portion extending along the covering in the space between the spaced-apart inflatable portions in said zone and having the margins of said inflatable portion in close proximity to adjacent margins of said spaced-apart inflatable portions, said inflatable portion being of lesser width than that of each of said spaced-apart inflatable portions and including fabric material of relatively high stretchability as compared to that of said stretch-resisting fabric material and being constructed and arranged for local inflation by virtue of its high stretchability without exerting substantial stretching force on said stretchable portion.

5. Apparatus for preventing the accumulation of ice on the leading edge of an airfoil, said apparatus comprising a covering of resilient rubber-like material for said leading edge having a tube zone extending along the covering and a stretchable portion between said zone and the margin of the covering, means for attaching said covering at said margin, a pair of inflatable tubes spaced-apart chordwise and extending spanwise along the covering in said zone, said tubes including stretch-resisting fabric material in the walls thereof and being constructed and arranged for imparting upon inflation a stretching force to said stretchable portion, and an inflatable tube extending spanwise along the covering in the space between the pair of inflatable tubes in said zone and being the sole inflatable means in said zone between said pair of inflatable tubes, said inflatable tube being of lesser width than that of each of said pair of inflatable tubes and including fabric material in the wall thereof of relatively high stretchability as compared to that of said stretch-resisting fabric material and being constructed and arranged for local inflation by virtue of its high stretchability without exerting substantial stretching force on said stretchable portion.
